(57) **CLAIM**

I claim the ornamental design for a storage case, as shown and described, except as disclaimed herein.

DESCRIPTION

FIG. 1 is a front view of a first embodiment of the storage case.

FIG. 2 is a rear view thereof.

FIG. 3 is a top view thereof.

FIG. 4 is a bottom view thereof.

FIG. 5 is a left view thereof, for which the right view would be a mirror image thereof.

FIG. 6 is a top/rear/right perspective view thereof.

FIG. 7 is a bottom/front/left perspective view thereof.

FIG. 8 is a front view of a second embodiment of the storage case.

FIG. 9 is a rear view thereof.

FIG. 10 is a top view thereof.

FIG. 11 is a bottom view thereof.

FIG. 12 is a left view thereof, for which the right view would be a mirror image thereof.

FIG. 13 is a top/rear/right perspective view thereof.

FIG. 14 is a bottom/front/left perspective view thereof.

FIG. 15 is a front view of a third embodiment of the storage case.

FIG. 16 is a rear view thereof.

FIG. 17 is a top view thereof.

FIG. 18 is a bottom view thereof.

FIG. 19 is a left view thereof, for which the right view would be a mirror image thereof.

FIG. 20 is a top/rear/right perspective view thereof; and,

FIG. 21 is a bottom/front/left perspective view thereof.

The side rings and ring retainers and the ridges on the unclaimed surface are included to show portions of the storage case that form no part of the claimed design.

The broken lines that define the bounds of the claimed design form no part thereof.
